UNITED STATES PATENT OFFICE.

GEORGE W. TODD, OF OMAHA, NEBRASKA, ASSIGNOR TO RHENA TODD, OF OMAHA, NEBRASKA.

DENTAL INSTRUMENT.

Application filed April 16, 1927. Serial No. 184,288

This invention relates to an instrument for use of dentists in the extraction of teeth. In this work it frequently happens that, on account of their condition the crowns become crushed or separated from the root or roots, and in such instances removal of the roots is often a difficult matter and results in loss of time of the patient and operator.

Also it is well known in dentistry that if the crown of the tooth becomes separated from the roots, it is often desirable to separate the roots to facilitate removal. Also that, in some instances, in the removal of the roots, they are so firmly embedded, that the jaw is injured or fractured in effecting their removal.

One of the objects of the invention is to provide an instrument which may have a rocking movement by the hand of an operator in readily forming recesses at the opposed sides of a tooth-root.

Another object is to provide an instrument of the class described by use of which a groove may be readily formed surrounding the root or roots of a tooth.

Still another object is to provide an instrument which may have a rocking movement for quickly separating the roots of a tooth when required.

30 The invention includes an instrument of such construction that by its use the root or roots of a tooth may be quickly removed without undue pain to the patient, all liability of injury to the jaw being eliminated, and which, by its use, the tissue which surrounds the root or roots will be left free from a lacerated or ragged condition, and will be ready for heating.

With the foregoing objects in view and others to be mentioned the invention presents a novel and useful construction, combination and arrangement of parts as described herein and claimed and as illustrated in the accompanying drawing, it being understood that changes may be made in form, size, proportion and minor details without departing from the spirit of the invention or sacrificing any of its advantages, said changes being determined by the scope of the invention as claimed.

50 In the drawing Fig. 1 is a plan view of a dental instrument, being one embodiment of the invention. Fig. 2 is an enlarged detail showing a part of one of the handles illustrated in Fig. 1. Fig. 3 is a view taken at

right angles to the view shown in Fig. 2. Fig. 4 is a view partly in section showing the roots of a tooth and a part of a jaw. Fig. 5 is a view showing a modified form of the invention. Fig. 6 is a sectional view to illustrate recesses or grooves formed in the jaw at the sides of a tooth.

Referring now to the drawing for a more particular description, numerals 6 and 7 indicate a pair of handles pivotally connected adjacent to one of their ends as indicated at 8, each handle preferably having a bow-shaped part 9 adjacent to the pivot 8, the handle 6 being provided with a terminal supporting element 10 outwardly of its bow-shaped part, and the handle 7 being provided with a serrated blade 11.

The general appearance of the instrument thus described is similar to various gripping instruments used by dentists.

The bow-shaped parts 9 are disposed opposite to each other and the serrated blade 11 is disposed opposite to the support 10, and a movement of the handles toward each other will cause a like movement of elements 9, 10 and 11.

The object in view in providing the opposed bow-shaped parts 9 is to permit a view of the teeth and parts adjacent thereto while operating, this being of advantage, 85 more particularly while operating upon teeth or roots of teeth in the lower jaw.

The use of the device will be appreciated by all persons familiar with dental work.

Removal of roots of teeth has generally been a difficult matter in instances where they are embedded in the jaws since no suitable contact with the roots can be made by gripping instruments usually employed.

The blade 11 has a curved cutting edge as clearly shown in the drawing, consisting of a plurality of teeth *a* of approximately V-shape.

While I do not wish to limit myself to the shape of the teeth of the blade, the "saw-tooth" shape, or shape used for ordinary saws is preferred.

Since the curvature of the blade is longitudinal, the instrument may have a rocking movement in the hand of an operator to cause the blade to incise either bone, hard tissue or the gums as may be required.

In instances where the crown or neck of a tooth has been broken or separated from the root or roots of a tooth and the broken

end of the root is disposed in the jaw bone, the instrument as described may be used and may have a rocking movement to form a groove *b*, said groove permitting a suitable contact for the jaws of a gripping instrument (not shown) for removing the root or roots *d*.

Another advantage in the use of the herein described instrument is that the edges of the gum *e*, adjacent to the roots *d* will be trimmed ready for healing after the roots have been removed.

The advantage in providing a removable mounting for the blade is to permit substitution of a new or different blade for one in present use. However, the blade may be constructed integral with a handle if desired.

While I have described a supporting-element 10, it will be understood that is a terminal part of a handle disposed opposite to the blade 11.

In operation the element 10 may engage a side of a root *d* as a guide or support while the serrated blade is forming a recess or groove *f* in the bone, at the side of a root.

It will be understood that all incisions are caused by a rocking movement of the implement, the result being that operation will be practically painless to the patient and may be quickly performed. Also, by its use, the roots of a tooth may be readily separated without causing appreciable pain.

While I have shown and described bow-shaped parts 9, this being the preferred construction, I do not wish to be understood as limiting myself in this respect. Also the blade may be provided with notches or teeth of any suitable shape.

The modified form of the invention shown in Fig. 5 of the drawing consists of a single handle 7' provided at one of its ends with a blade 11' having a longitudinally curved edge provided with teeth *a'*. This instrument may be used in forming recesses or grooves *b* the same as described, the instrument having a rocking movement for these purposes.

It will thus be seen that, by a rocking movement of the implement incisions may be formed in the bone at a side or at opposed sides of a tooth adjacent to its root or roots to facilitate removal by use of an elevator or forceps, any use of "chisel and mallet" sometimes resorted to, being dispensed with. Also it will be noted that the instrument is of great advantage in instances where the growth of the bone has caused it to be united with the tooth, as well as in instances where there has been an abnormal growth of the root or roots of a tooth to cause projections or enlargements of a root in the bone, for in all instances, by use of the instrument,

the tooth may be separated from the bone, ready for removal, the result being that roots of teeth may be readily removed regardless of their form and without injury to the bone and without liability of breaking the root or roots during operation.

It is proper to state that the V shaped teeth may be of attenuated form with edges of knife-like sharpness, this construction for the teeth being of advantage in certain operations, but I do not wish to limit myself to this feature. Also, as shown in Fig. 1 of the drawing, the blade at the end of one handle projects somewhat beyond the end of the other handle, this being obviously of advantage to permit the blade 11 to move in an arc outwardly of the support 10, during the rocking movements of the instrument.

I claim as my invention:—

1. In a dental instrument, a pair of pivotally connected handles providing a jaw and a second jaw at their distal ends, the first named jaw having a concaved inner surface and a convergent terminal, a saw-blade mounted on the second jaw, the parts being of such proportion that said convergent terminal will normally be disposed in a plane between the ends of the saw-blade.

2. In a dental instrument, a pair of pivotally connected handles providing a jaw and a second jaw at their distal ends, the first named jaw having a concaved inner surface, a saw-blade mounted on the second jaw, the parts being of such proportion that the outer end of the first named jaw will normally be disposed in a plane between the ends of the saw-blade.

3. In a dental instrument, a pair of pivotally connected handles providing a jaw and second jaw at their distal ends, a rectilinear blade mounted on the second jaw having an outwardly curved row of teeth, the parts being so proportioned that the outer end of the first named jaw is normally disposed in a plane between the ends of said row of teeth.

4. In a dental instrument, a pair of pivotally connected handles providing a jaw and a second jaw at their distal ends, said first named jaw having a concaved inner surface and a convergent terminal, a rectilinear blade mounted on the second jaw provided with an outwardly curved row of teeth, the proportion of parts being such that the convergent terminal of the first named jaw is normally disposed in a plane between the ends of said row of teeth.

In testimony whereof, I have affixed my signature.

GEORGE W. TODD.
